[57] CLAIM

The ornamental design for cover for shutting off sun-
shine on roof of car, as shown and described.

DESCRIPTION

FIG. 1 is a perspective view of a cover for shutting off
sunshine on roof of car, showing my new design;

FIG. 2 is a front elevational view thereof;

FIG. 3 is a top plan view thereof;

FIG. 4 is a bottom plan view thereof;

FIG. 5 is a side elevational view thereof;

FIG. 6 is a sectional view taken along the line 6—6 of
FIG. 5;

FIG. 7 is a front elevational view at storing condition
thereof; and,

FIG. 8 is a perspective view thereof, on a reduced scale,
in position of use on a car which is fragmentarily shown
in broken lines for illustrative purposes only and forms
no part of the claimed design.

FIG. 1**FIG. 2****FIG. 3****FIG. 4****FIG. 5****FIG. 7****FIG. 6****FIG. 8**
